STAPLING MACHINE

Sidney M. Berger, Brooklyn, N. Y.

Application February 19, 1951, Serial No. 211,620

23 Claims. (Cl. 1—48)

1

This invention relates to stapling machines, and more particularly to stapling machines of the plier type.

A main object of the invention is to provide a novel and improved stapling machine which is especially adaptable for stapling upholstery, said machine being very simple in construction, being easy to operate, and providing automatic feed, forming, and closure of the staples fabricated thereby, the machine being adapted to be operated with only one hand.

A further object of the invention is to provide an improved stapling machine of the plier type which is inexpensive to manufacture, which is rugged in construction, which is especially adapted for fastening fabric or other flexible covers, such as automobile seat covers and the like, in a rapid and convenient manner, and which requires the use of only one hand for the manipulation thereof.

A still further object of the invention is to provide an improved stapler of the plier type which includes wire feed means operated automatically in response to actuation of the staple cutting and forming means of the apparatus, the wire feed means and source of wire being included as a unitary part of the apparatus.

A still further object of the invention is to provide an improved stapling machine of the plier type which is arranged to be operated by one hand of the user so that the other hand of the user may be employed for holding the fabric or other flexible sheet material to be stapled, the stapling machine being particularly useful in fastening seat covers to automobile seats.

A still further object of the invention is to provide an improved automatic stapling machine for forming "hog rings" as employed in fastening automobile seat covers to seat frames, the machine providing rapid and efficient formation of the rings from wire stock carried on the machine, whereby the use of prefabricated "hog rings" is not required in securing automobile seat covers and the like when the machine of the present invention is employed.

Further objects and advantages of the invention will become apparent from the following description and claims, and from the accompanying drawings, wherein:

Figure 1 is a top plan view of one form of stapling machine constructed in accordance with the present invention.

Figure 2 is a fragmentary top plan view of the machine of Figure 1 showing the fulcrum element of the machine in an outwardly withdrawn position.

2

Figure 3 is a longitudinal cross-sectional view taken on the line 3—3 of Figure 1.

Figure 4 is a longitudinal cross-sectional view similar to Figure 3 but showing the forming jaw elements of the machine in closed positions at the end of a stapling operation, said view being taken on line 4—4 of Figure 2.

Figure 5 is a side elevational view of one of the major body segments of the machine of Figures 1 to 4.

Figure 6 is a transverse vertical cross-sectional view taken on line 6—6 of Figure 1.

Figure 7 is a transverse vertical cross-sectional view taken on line 7—7 of Figure 1.

Figure 8 is a transverse vertical cross-sectional view taken on line 8—8 of Figure 1.

Figure 9 is a transverse vertical cross-sectional view taken on line 9—9 of Figure 1.

Figure 10 is an enlarged longitudinal cross-sectional detail view showing the relationship of the staple-forming die elements in the positions thereof shown in Figure 3.

Figure 11 is a top plan detail view of the structure shown in Figure 10.

Figure 12 is an elevational detail view taken on the line 12—12 of Figure 1.

Figure 13 is a longitudinal vertical cross-sectional view taken through a modified form of stapling machine constructed in accordance with the present invention.

Figure 14 is a view similar to Figure 13 but showing the staple-forming die elements in open positions at the beginning of a stapling operation.

Figure 15 is an enlarged cross-sectional detail view taken on the line 15—15 of Figure 13.

Referring to the drawings, and more particularly to Figures 1 to 12, one form of the stapling machine may comprise a pair of mating body segments 21 and 22 which are suitably recessed to define a housing for the various internal components of the machine, as will be presently described. As shown in Figures 4 and 5, the mating body segments 21 and 22 may be recessed at their forward portions, as shown at 23 and 24 to define a cavity which is open at its top end. The body segments may be further recessed, as shown at 25, 26, 27 and 28 in Figure 5, and as shown at 29 and 30 in Figure 4. In addition,

the body segments are formed with mating longitudinal grooves 31 and 32 defining a longitudinally extending bore for the wire which is fed to the forming dies of the tool.

The rear end portions of the respective body segments 21 and 22 are provided with downwardly and rearwardly inclined bracket lugs 33

and 34 between the ends of which is journalled a reel 35 adapted to carry a coil of wire stock.

The forward portions of the body segments 21 and 22 are secured together by a transverse rivet 36 which traverses the cavity defined by the recesses 23 and 24, as shown. Designated at 37 is a transverse shaft element which is rotatably mounted in the mating body segments 21 and 22 and is located in the upper portion of the recess 25. Designated at 38 is another transverse shaft element which is rotatably mounted in the mating body segments 21 and 22 and which traverses said body segments at the intermediate portion of the recess 26. Designated at 39 is still another transverse shaft element which is rotatably mounted in the mating body segments and which is located in the recess 27.

Designated at 40 is an arm which is secured to shaft element 37 and which extends outside the main body defined by segments 21 and 22. As shown, arm 40 extends through the recess 25 and is formed with the grip portion 41. Said grip portion is biased clockwise, as viewed in Figure 3, by a suitable spring 42 connecting arm 40 to the forward portion of the main body. As shown in Figure 4, the grip portion 41 is shaped so that it may be disposed adjacent the main body, said grip portion being urged away from the main body by the spring 42 but being movable to a position adjacent said main body by grasping the main body and said grip portion 41 in one hand and exerting squeezing pressure thereon.

Obviously, any other suitable spring means may be employed to bias grip portion 41 away from the main body of the tool, such as a leaf spring connected between the grip portion and the main body in the manner illustrated in Figures 13 to 15.

Secured to shaft 37 is a gear segment 43 which meshes with a rack bar 44 slidably mounted in the cavity defined between body segments 21 and 22. Rack bar 44 is provided with upper rack teeth 45 and with lower rack teeth 46. Segment 43 meshes with the upper rack teeth 45.

Secured to shaft 36 is a gear segment 47 which meshes with the upper rack teeth 45 of rack bar 44. Integrally formed with said gear segment 47 is a concave die element 48 which is located at the right side of shaft 36, as viewed in Figure 3, and which is rotatable in the cavity defined by recesses 23 and 24. The rear end wall of said cavity is arcuate in shape, and the end of die element 48 is also arcuate and is arranged to move slidably along said rear end wall of the cavity when the die element 48 is rotated. The bore defined by grooves 31 and 32 terminates at said rear end wall, whereby the end of die element 48 acts as a shearing element to shear off a length of wire projecting from said bore when the die element 48 is rotated upwardly from the position thereof shown in Figure 3. This rotation occurs when arm 40 is rotated counterclockwise, as viewed in Figure 3, since rack bar 44 is moved rearwardly responsive to counterclockwise rotation of arm 40.

Rotatably mounted on shaft 36 is a gear segment 49, and integrally formed with gear segment 49 is a concave die element 50 located at the left side of shaft 36, as viewed in Figure 3, and opposing the concave die element 48. Die element 50 is rotatable in the cavity defined by recesses 23 and 24. Gear segment 49 meshes with a rack bar 51 slidably mounted in the main body of the tool adjacent to rack bar 44, said rack bar 51 being movable longitudinally in said main body.

Secured on the shaft 38 is a relatively small gear 52 which meshes with the lower teeth of rack bar 44 and with the teeth of rack bar 51, as shown in Figure 3. It will be apparent that when rack bar 44 is moved to the right, as viewed in Figure 3, rack bar 51 will be moved to the left, and vice versa. Therefore, when die element 48 is rotated counterclockwise, the opposing die element 50 is rotated clockwise at the same rate. Furthermore, when grip portion 41 is rotated to the closed position thereof shown in Figure 4, the die elements 48 and 50 are rotated from the open positions shown in Figure 3 to the closed positions shown in Figure 4.

Secured on shaft 38 adjacent small gear 52 is the relatively large gear 53. Slidably mounted in the recessed portion 29 of the cavity defined between body segments 21 and 22 is a rack bar 54 which is disposed above and which meshingly engages with gear 53. Designated at 55 is a lever which is pivoted at 56 in body segment 21 for rotation in a plane normal to the planes of rotation of the die elements 48 and 50. The forward end of lever 55 is formed with a fulcrum element 57 movable into a position above the shaft element 36 substantially between the extremities of the die elements 48 and 50, as shown in Figures 1 and 3. The rear portion 58 of lever 55 is received in a slot 59 formed in the upper portion of segment 21. Said rear portion 58 is formed with a sinuous cam slot 60 which slidably receives an upstanding pin 61 secured on the rack bar 54. Slot 60 is shaped to move fulcrum element 57 out of the space between the die elements 48 and 50 after a preliminary stage of upward rotation of said die elements. After said preliminary upward rotation of the die elements, during which fulcrum elements 57 is employed as a support for the intermediate portion of a length of wire while the ends of the wire are bent upwardly, the fulcrum element is withdrawn by the camming action of pin 61 on slot 60 as rack bar 54 is moved rearwardly. It will be apparent that as soon as the ends of the wire have been bent upwardly, continued inward pressure of the die elements is sufficient to complete the bending of the wire without further need for a fulcrum element.

It will be seen that the recesses 28 and 30 define a longitudinal cylindrical bore 66. Slidably positioned therein is a sleeve member 62 whose central bore is in registry with the bore defined by the grooves 31 and 32. From Figure 3 it will be apparent that the wire from reel 35, shown at 63, extends slidably through a guide plug 64 secured in the end of the tool body and through the central bore of sleeve 62 and the bore defined by grooves 31 and 32.

Designated at 65 is a large coiled spring disposed in the bore 66 and bearing between sleeve 62 and plug 64. Spring 65 biases sleeve 62 to the left, as viewed in Figure 4. Sleeve 62 is provided with a friction clutch comprising a spring-pressed ball 67 arranged in an inclined bore 68 in said sleeve and engaging the wire 63. The ball 67 allows sleeve 62 to be moved freely to the right relative to wire 63, as viewed in Figure 3, but grips the wire when the sleeve is returned to the left by the wedging action of the ball 67 thereon.

Movement of the wire 63 to the right, as viewed in Figure 3, is prevented by a spring-pressed clutch ball 69, similar to ball 67, provided in the tool body and arranged to exert braking force downwardly and forwardly on the wire 63, the clutch ball 69 being housed in a downwardly and

forwardly inclined sleeve 10 threadedly engaged in the body forwardly of the bore 66, as shown in Figure 3.

The rack bar 54 is in abutment with the sleeve 62 and moves the sleeve 62 rearwardly at the same time that the concave die elements 48 and 50 are rotated upwardly towards each other. This occurs when grip 41 is rotated counterclockwise from the position of Figure 3. Designated at 71 is an arm pivoted on shaft element 39 in recess 27 and located below sleeve 62 when said sleeve is in the position of Figure 3. Arm 71 is biased counterclockwise by a leaf spring 72 secured in the wall of recess 27 and bearing downwardly on the left end portion of said arm, as viewed in Figure 3. When sleeve 62 is moved by rack bar 54 to the right, as viewed in Figure 3, to the position thereof shown in Figure 4, the arm 71 lockingly engages against the end of sleeve 62, as shown, and prevents immediate return of said sleeve when rack bar 54 returns towards its initial position. However, when the die elements 48 and 50 have returned to their initial open positions, as shown in Figure 3, the left end 73 of arm 71 is cammingly engaged by the right end of rack bar 54, causing said arm 71 to be rotated clockwise, as viewed in Figure 4, thereby releasing sleeve 62 and allowing spring 65 to return the sleeve to the position of Figure 3. This, of course, advances the wire 63 and brings a new length of wire over the die elements 50 and 48.

The die element 50 is formed at its extremity with a notch 74 adapted to receive the end of the wire advanced into forming position by the return of sleeve 62 as above described. When grip member 41 is rotated counterclockwise from the position of Figure 3 toward the position of Figure 4, die element 48 shears the wire, and the ends of the wire are bent upwardly around the fulcrum element 57 in a first stage of the rotation of the grip member 41 toward the tool body. As rotation of grip member 41 toward the tool body is continued, the fulcrum element 57 is retracted from between the die elements and the wire is bent into substantially circular form, as shown in Figure 4, by the opposed concave forming surfaces of the die elements.

It will be understood that the ring thus formed may be employed to staple a portion of flexible sheet material, such as fabric, to a portion of a seat frame. It will be further apparent that the stapling operation may be accomplished with only one hand, since it is merely necessary to grasp the body of the tool and the grip portion in one hand, exerting squeezing pressure thereon. Upon relaxation of said pressure, the grip member 41 returns to its initial position, causing the rack bar 54 to trip the detent arm 71, whereby a new length of wire is advanced over the forming die elements 48 and 50 by sleeve 62.

The concave die elements 48 and 50 are formed with centering recesses 75 and 76 to maintain the wire in centered position between the die elements during the ring-forming operation.

Referring now to the form of the invention illustrated in Figures 13, 14 and 15, 81 designates a first arm, and 82 designates a second arm which is pivotally connected to arm 81 at 83. Secured between the arms 81 and 82 is a leaf spring 84 which biases the arms apart.

Secured to the rear end portion of arm 81 are a pair of downwardly and rearwardly inclined lugs 85 between the ends of which is journaled the reel 86 adapted to carry a coil of wire stock. The arm 81 is formed with a longitudinal

bore 87 in which the wire from reel 86 is slidably received. The forward portion of arm 81 is formed with an inclined, rearwardly directed recess 88 communicating with bore 87. A spring-pressed ball 89 is provided in the recess 88 which wedgingly engages the wire, shown at 90, when the wire is moved rearwardly, thus preventing rearward movement of said wire in bore 87 but allowing the wire to be freely moved forwardly therein.

Arm 81 is formed at its intermediate portion with a large slot 91. Designated at 92 is a wire-gripping sleeve similar to sleeve 62 in the previously-described form of the invention. Sleeve 92 surrounds the wire 90 and is provided with wire-gripping means similar to the spring-pressed ball 67 in the inclined bore 68 previously described. Designated at 93 is a large coiled spring mounted in a recess 94 and bearing between sleeve 92 and the end wall of said recess, as shown, biasing sleeve 92 forwardly.

Sleeve 92 is formed with an upstanding longitudinal rib 95 provided with transverse projections 96, 96 which slidably engage in opposed longitudinal grooves 97 formed in the side walls of slot 91 and guide sleeve 92 for longitudinal movement in slot 91. Designated at 98 is a link arm which is pivoted to arm 82 at 99 and which is formed at its end with a head 100. Head 100 is slidably received in slot 91 and is provided with transverse projections 101 slidably engaged in opposed longitudinal grooves 102 formed in the side walls of slot 91 and guiding head 100 for longitudinal movement in slot 91.

Designated at 103 is a rearwardly extending lever pivoted between the side walls of slot 91 at 104. The free end of lever 103 comprises an upwardly projecting, tapered detent element 105 adapted to lockingly engage in a notch 106 formed in the bottom of sleeve 92. Detent element 105 is biased upwardly by a spring 107 secured between lever 103 and the bottom wall of the cavity 91, as shown.

The rear end of head 100 is adapted to abut the sleeve 92 and move the sleeve rearwardly responsive to rotation of arm 82 toward arm 81. When sleeve 92 has been moved rearwardly to a position adjacent the opening of bore 94, as shown in Figure 15, the detent element 105 engages in notch 106 and locks sleeve 92.

The forward end of head 100 comprises a lug 108 which is adapted to abut a bevelled shoulder 109 on the forward portion of lever 103 when the arm 82 is allowed to separate from arm 81 to its fully released position shown in Figure 14. When lug 108 engages shoulder 109, the lever 103 is rotated downwardly, disengaging detent element 105 from notch 106 and allowing sleeve 92 to be moved forwardly by the expansion of spring 93. This advances a length of wire through the arm 81. Therefore, a new length of wire is advanced through arm 81 each time arms 81, 82 are squeezed together and then released.

The forward portion of arm 82 is formed with a concave die element 110 terminating in a shearing element 111. Arm 81 is formed with a slot-like recess 112 in which die element 110 is rotatable, and the shearing element 111 is arranged to move along the rear wall surface of recess 112 responsive to the rotation of arm 82 relative to arm 81. The wire 90 protrudes from the rear wall surface of recess 112 and is sheared by element 111 when said element moves upwardly from the position of Figure 14.

Designated at 115 is a concave die element

which is pivoted to the forward end of arm 81 at 116 and which faces the die element 110. The die element 115 is provided with the gear 117 rigidly secured thereto and which meshes with gear teeth 118 formed on the end of arm 82, as shown, whereby counterclockwise rotation of arm 82 drives die element 115 clockwise, and vice versa.

Designated at 119, 119 are a pair of opposed fulcrum arms pivoted in the opposing walls of recess 112 at 120, 120 for rotation in a transverse plane relative to said recess, and biased inwardly by respective leaf springs 121, 121 arranged as shown in Figure 15. The fulcrum arms 119, 119 are formed with opposing bearing recesses 122, 122, adapted to embrace the length of wire disposed over recess 112 when arm 82 is in the position shown in Figure 14. Said arms 119, 119 are provided with inwardly facing opposing cam surfaces at 123, 123 which are adapted to be engaged by the rounded end portion 124 of arm 82 when arm 82 is rotated counterclockwise, as viewed in Figure 14. Portion 124 exerts upward wedging action on the arms 119, 119, and, after a preliminary stage of rotation of arm 82, spreads apart the arms 119, 119 to release the wire blank after the ends of the wire have been bent upwardly by the concave die elements.

At the beginning of the stapling operation the wire is arranged as shown in Figure 14. When arm 82 is rotated toward arm 81, as by exerting squeezing pressure on said arms, element 111 shears off a length of wire, said length being gripped by the fulcrum arms 119, 119 at their bearing recesses 122, 122. During the first stage of rotation of arm 82 toward arm 81 the opposing concave die elements 110 and 115 bend the ends of the wire upwardly, the intermediate portion of the wire being held by fulcrum arms 119, 119. As rotation of arm 82 toward arm 81 continues, the fulcrum elements 119, 119 are separated, allowing the concave die elements 110 and 115 to complete the stapling operation, forming the circular fastening ring from the wire blank and engaging said ring around the parts to be stapled. The sleeve 92 is at the same time moved rearwardly to the position of Figure 15. When the squeezing pressure on the arms 81 and 82 is released, spring 84 returns the arms to their spread-apart positions. When lug 108 engages bevelled shoulder 109, the lever 103 is tripped, releasing sleeve 92, whereby said sleeve moves forwardly and advances a new length of wire over recess 112. The tool is now ready for the next stapling operation.

While certain specific embodiments of a stapling tool have been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In a stapling machine of the plier type, a pair of arms pivotally connected together, wire feed means on one of said arms operated responsive to a first stage of relative rotation thereof, wire shearing means on one arm arranged to cut off a length of wire responsive to a second stage of relative rotation of said arms, a first concave die element secured to said one of the arms opposing said wire shearing means, a second concave die element on said one arm opposing said first die element, a movable fulcrum element on said one of the arms and being movable between said die elements, and means withdrawing said

fulcrum element from between the die elements responsive to a succeeding stage of relative rotation of said arms.

2. In a stapling machine of the plier type, a pair of arms pivotally connected together, wire feed means on one of the arms, a shearing element cooperatively arranged with respect to said wire feed means to cut off a length of wire responsive to a first stage of relative rotation of said arms, a first concave die element secured to said one of the arms opposing said shearing element, a second concave die element, means supporting said second concave die element in rotative opposing relation with respect to said first concave die element, a fulcrum element movably secured to said one of the arms and being movable between said die elements, and means mechanically coupled to said arms and arranged to retract the fulcrum element from between said die elements responsive to a succeeding stage of relative rotation of said arms.

3. In a stapling machine of the plier type, a pair of arms pivotally connected together, wire feed means on one of the arms, a shearing element cooperating with said one of the arms to cut off a length of wire responsive to a first stage of relative rotation of said arms, a first concave die element secured to said one of the arms opposing said shearing element, a second concave die element, means supporting said second concave die element in rotative opposing relation with respect to said first die element, a fulcrum element movably secured to said one of the arms and being movable between said die elements, and means withdrawing said fulcrum element responsive to a succeeding stage of relative rotation of said arms.

4. In a stapling machine of the plier type, a pair of arms pivotally connected together, wire feed means on one of the arms operated responsive to relative rotation of the arms, a shearing element cooperating with said one of the arms to cut off a length of wire responsive to a first stage of relative rotation of said arms, a first concave die element mounted on said one of the arms opposing said shearing element, a second concave die element, means supporting said second concave die element in rotative opposing relation with respect to said first die element, a fulcrum element movably secured to said one of the arms and being movable between said die elements, and means withdrawing said fulcrum element responsive to a succeeding stage of relative rotation of said arms.

5. In a stapling machine of the plier type, a pair of arms pivotally connected together, wire feed means on one of the arms operated responsive to relative rotation of the arms, a shearing element cooperating with said one of the arms to cut off a length of wire responsive to a first stage of relative rotation of said arms, a first concave die element pivoted to said one of the arms opposing said shearing element, means coupling said first concave die element to said other arm, a second concave die element, means supporting said second concave die element in rotative opposing relation with respect to and facing said first die element, a fulcrum element movably secured to said one of the arms and being movable between said die elements, and means withdrawing said fulcrum element responsive to a succeeding stage of relative rotation of said arms.

6. In a stapling machine of the plier type, a pair of arms pivotally connected together, wire feed means on one of the arms operated responsive

sive to relative rotation of the arms, a shearing element cooperating with said one of the arms to cut off a length of wire responsive to a first stage of relative rotation of said arms, a first concave die element pivoted to said one of the arms opposing said shearing element, means coupling said first concave die element to said other arm, a second concave die element, means supporting said second concave die element in rotative opposing relation with respect to said first die element, a fulcrum element movably secured to said one of the arms and being movable between said die elements, and means withdrawing said fulcrum element responsive to a succeeding stage of relative rotation of said arms, said coupling means being arranged to rotate said first concave die element toward said shearing element responsive to said first stage of relative rotation.

7. In a stapling machine of the plier type, a pair of arms pivotally connected together, wire feed means on one of the arms, a shearing element cooperating with said one of the arms to cut off a length of wire responsive to a first stage of relative rotation of said arms, a first concave die element pivoted to said one of the arms opposing said shearing element, means gearingly coupling said first die element to said other arm and arranged to rotate said first concave die element toward said shearing element responsive to said first stage of relative rotation, a second concave die element, means supporting said second concave die element in rotative opposing relation with respect to said first die element, a fulcrum element movably secured to said one of the arms and being movable between said die elements, and means retracting said fulcrum element from between said die elements responsive to a succeeding stage of relative rotation of the arms.

8. In a stapling machine of the plier type, a pair of arms pivotally connected together, wire feed means on one of the arms, a shearing element cooperating with said one of the arms to cut off a length of wire responsive to a first stage of relative rotation of said arms, a first concave die element pivoted to said one of the arms opposing said shearing element, means gearingly coupling said first die element to said other arm and arranged to rotate said first concave die element toward said shearing element responsive to said first stage of relative rotation, a second concave die element, means supporting said second concave die element in rotative opposing relation with respect to said first die element, a fulcrum element movably secured to said one of the arms, means biasing said fulcrum element to a position between said die elements, and means retracting said fulcrum element from between said die elements responsive to a succeeding stage of relative rotation of the arms.

9. In a stapling machine of the plier type, a pair of arms pivotally connected together, wire feed means on one of the arms, a shearing element cooperating with said one of the arms to cut off a length of wire responsive to a first stage of relative rotation of said arms, a first concave die element pivoted to said one of the arms opposing said shearing element, means gearingly coupling said first die element to said other arm and arranged to rotate said first concave die element toward said shearing element responsive to said first stage of relative rotation, a second concave die element, means supporting said second concave die element in rotative opposing relation with respect to said first die element, a fulcrum element movably secured to said one of the arms,

means biasing said fulcrum element to a position between said die elements, and cam means controlled by said other arm and cammingly engaging said fulcrum element, said last-named means being arranged to retract said fulcrum element from between said die elements responsive to a succeeding stage of relative rotation of the arms.

10. A stapling machine of the plier type comprising a pair of arms pivotally connected together at their intermediate portions and having rear grip elements and forward jaw elements, means biasing said rear grip elements apart, wire feed means on one of the arms and arranged to feed wire forwardly therethrough responsive to rotation of said grip elements apart, a shearing member cooperating with said one of the arms and arranged to cut off a length of wire responsive to a first stage of rotation of said grip elements towards each other, a first concave die element secured to the jaw element of said one of the arms opposite said shearing member, a second concave die element, means supporting said second concave die element in rotative opposing relation with respect to the first die element, a fulcrum element movably secured to said one of the arms, means positioning said fulcrum element between said die elements when said grip elements are in spread-apart relationship, and means withdrawing said fulcrum element from between said die elements responsive to a second stage of rotation of said grip elements towards each other.

11. A stapling machine of the plier type comprising a pair of arms pivotally connected together at their intermediate portions and having rear grip elements and forward jaw elements, means biasing said rear grip elements apart, wire feed means on one of the arms and arranged to feed wire forwardly therethrough responsive to rotation of said grip elements apart, a shearing member cooperating with said one of the arms and arranged to cut off a length of wire responsive to a first stage of rotation of said grip elements towards each other, a first concave die element pivoted to the jaw element of said one of the arms opposite said shearing member, a second concave die element, means supporting said second concave die element in rotative opposing relation with respect to the first die element, means gearingly coupling said first concave die element to said other arm and arranged to rotate said first concave die element towards the second concave die element responsive to rotation of the grip elements towards each other, a fulcrum element movably secured to said one of the arms, means positioning said fulcrum element between said die elements when said grip elements are in spread-apart relationship, and means withdrawing said fulcrum element from between said die elements responsive to a second stage of rotation of said grip elements towards each other.

12. In a stapling machine of the plier type, a pair of arms pivotally connected together, a pair of concave, opposing forming dies on said arms, wire feed means on one of the arms operated responsive to relative rotation of the arms and arranged to move a length of wire over said forming dies, wire shearing means arranged to cut off said length of wire responsive to a first stage of relative rotation of the arms and to place said length of wire between the dies, a fulcrum element movably secured to said one of the arms, means biasing said fulcrum element to a position between the dies, and means retract-

ing said fulcrum element responsive to a second stage of relative rotation of said arms.

13. The structure of claim 12, and wherein said feed means comprises a sleeve member slidable longitudinally in said one arm, wire gripping means in said sleeve member, an abutment member coupled to the other arm and engageable with said sleeve member, said abutment member being arranged to move the sleeve member rearwardly responsive to rotation of the rear portions of the arms toward each other, spring means biasing the sleeve member forwardly, movable detent means lockingly engageable with the sleeve member when said sleeve member has been moved rearwardly a predetermined distance, and means disengaging said detent means from said sleeve member responsive to the relative outward rotation of the rear portions of said arms to a predetermined angle of separation.

14. In a stapling machine of the type having a pair of arms pivotally connected together and provided with wire forming means adjacent the ends of the arms, wire feed means comprising a sleeve member slidable longitudinally in one of the arms, wire gripping means in said sleeve member, an abutment member coupled to the other arm and engageable with said sleeve member, said abutment member being arranged to move the sleeve member rearwardly responsive to rotation of the rear portions of the arms toward each other, spring means biasing the sleeve member forwardly, movable detent means lockingly engageable with the sleeve member when said sleeve member has been moved rearwardly a predetermined distance, and means disengaging said detent means from said sleeve member responsive to the relative outward rotation of the rear portions of said arms to a predetermined angle of separation.

15. In a stapling machine of the type having a pair of arms pivotally connected together and provided with wire forming means adjacent the forward end portions of the arms, wire feed means comprising a wire gripping member slidable longitudinally in one of the arms, an abutment member coupled to the other arm and engageable with the wire gripping member, said abutment member being arranged to move the wire gripping member rearwardly responsive to rotation of the arms in one direction, spring means biasing the wire gripping member forwardly, movable detent means lockingly engageable with the wire gripping member when said wire gripping member has been moved rearwardly a predetermined distance, and means disengaging said detent means from said wire gripping member responsive to the rotation of said arms in the opposite direction to a predetermined angle of separation.

16. In a plier tool, a pair of pivoted arms, a pair of pivoted opposed concave staple forming elements actuated by said arms, means for feeding wire stock to said elements, and shearing means on one of said elements operable to cut a staple length of wire upon initial staple forming movement of said elements.

17. In a plier tool, a pair of pivoted arms, a pair of opposed concave pivoted staple forming elements actuated by said arms, means for feeding wire stock to said elements, and shearing means on one of said elements operable to cut a staple length of wire upon initial staple forming movement of said elements, one of said staple forming elements being rigidly connected to one of said pivoted arms.

18. A plier type stapling tool as described in

claim 16, wherein said pair of staple-forming elements comprise semi-circular die surfaces which are pivoted to rotate with respect to each other to form said cut length of staple wire into a ring-shaped staple.

19. A pair of forming dies for use in a staple forming tool of the plier type having biased-apart pivoted arms and means for feeding wire stock to a staple forming position upon spreading movement of said arms; said pair of forming dies comprising pivoted members having concave forming surfaces swingable toward each other to form a ring-shaped staple from a portion of said wire stock, said dies further having separate portions for engagement with actuating mechanism operated by closing movement of said pivoted arms to swing said forming surfaces toward each other.

20. In a plier type stapling tool, a pair of biased-apart pivoted arms, a pair of pivoted staple forming elements operated by closing movement of said arms, and means for feeding wire stock to said elements at the completion of spreading movement of said arms to their biased-apart positions, said wire feeding means comprising a clutch member moved along said wire away from said staple forming elements against pressure means upon closing movement of said arms, a latch for retaining said clutch member in its furthermost position while said arms are being spread apart, and a trip member for releasing said latch at the end of said spreading movement of said arms to permit said pressure means to move the clutch and feed wire toward said staple forming elements.

21. In a stapling machine of the plier type, a pair of arms pivotally connected together, wire feed means on one of the arms, shearing means cooperatively arranged with respect to said wire feed means to cut off a length of wire responsive to a first stage of relative rotation of said arms, a first concave die element secured to said one of the arms opposing said shearing means, a second concave die element, means supporting said second concave die element in rotative opposing relation with respect to said first concave die element, fulcrum means movably secured to one of the arms and being movable between said die elements, and means arranged to retract said fulcrum means from between said die elements responsive to a succeeding stage of relative rotation of said arms.

22. In a stapling machine of the plier type, a pair of arms pivotally connected together, wire feed means on one of the arms, shearing means cooperatively arranged with respect to said wire feed means to cut off a length of wire responsive to a first stage of relative rotation of said arms, a first concave die element secured to said one of the arms opposing said shearing means, a second concave die element, means supporting said second concave die element in rotative opposing relation with respect to said first concave die element, fulcrum means movably secured to one of the arms and being movable between said die elements, means biasing said fulcrum means to a position between said die elements, and means arranged to retract said fulcrum means from between said die elements responsive to a succeeding stage of relative rotation of said arms.

23. In a stapling machine of the plier type, a pair of arms pivotally connected together, wire feed means on one of the arms, shearing means cooperatively arranged with respect to said wire feed means to cut off a length of wire responsive to a first stage of relative rotation of said arms,

a first concave die element secured to said one of the arms opposing said shearing means, a second concave die element, means supporting said second concave die element adjacent said shearing means in rotative opposing relation with respect to said first concave die element, fulcrum means movably secured to one of the arms and being movable between said die elements, means biasing said fulcrum means to a position between said die elements, and means arranged to retract said fulcrum means from between said die elements

responsive to a succeeding stage of relative rotation of said arms.
